HANDLE AND METHOD OF MAKING SAME

Filed Jan. 10, 1923

FIG. 1.

FIG. 2.

FIG. 3.

FIG. 4.

FIG. 5.

INVENTOR
MORRIS J. GOLDMAN
BY *Fritz Ziegler Jr.*
ATTORNEY

UNITED STATES PATENT OFFICE.

MORRIS JACOB GOLDMAN, OF STATEN ISLAND, NEW YORK.

HANDLE AND METHOD OF MAKING SAME.

Application filed January 10, 1923. Serial No. 611,700.

To all whom it may concern:

Be it known that I, MORRIS JACOB GOLDMAN, a citizen of the United States, and resident of Staten Island, in the county of Richmond and State of New York, have invented certain new and useful Improvements in Handles and Methods of Making Same, of which the following is a specification.

This invention relates to handles such as 10 are used for luggage and similar leather articles and has for its principal object to improve upon the construction of the handle and also to provide a new and improved method for constructing the handle.

15 It has heretofore been a common practice to construct these handles with a metal reinforcing rod encased in a plurality of folds or wrappers of paper suitably shaped to provide a handle grip, and to cover the paper 20 with a strip of leather which is pounded and worked to the desired curvature and then cemented or glued to the paper, the overlapping edges of the leather strip being joined together on the top of the grip by 25 sewing a seam through the edges as close to the grip as possible, after which the surplus leather of the overlapping edges is cut or trimmed off. This type of grip is expensive to make because of the labor required, and 30 also because of the waste of leather, it being necessary to leave a wide margin of leather for the overlapping edges in order to provide a sufficient amount of material to be received in the sewing machine which has to 35 be trimmed off after the seam is completed. Furthermore, the seam produces an objectionable projecting ridge and the threads of the seam break after the handle is in use a short time allowing the leather covering 40 to become detached thereby necessitating frequent repairs.

I am aware that it has been proposed to make the handle foundation of a pair of similar halves of sheet metal which are soldered together, but the handle having the sheet metal filling is not only subject to the objections noted above, as the leather covering must be sewed in the same manner but is also subject to the objection that the 45 leather covering can not readily be glued or cemented to the metal.

A further object of this invention is to provide a new and improved construction for an article of this type which will not 50 only involve less labor costs for its produc-

tion, and require less material for its construction, but which will be more substantial and therefore give better service but by presenting a substantially smooth surface without projecting ridges will present a 60 more pleasing appearance as well as afford a more comfortable grip for the hands.

For the accomplishment of these and such further objects as will hereinafter be apparent to those skilled in the art to which this 65 appertains, the invention consists in a method for producing the handle and in the construction, combination and arrangement of the parts of the handle as herein specifically described and illustrated in the accompanying drawings wherein is shown a preferred embodiment of the invention, but it is to be understood that changes, variations and modifications may be resorted to 70 which fall within the scope of the claims 75 hereunto appended.

In the drawings forming a portion of this specification and wherein like reference characters indicate corresponding parts 80 through the several views,

Fig. 1 is a perspective view of the foundation or filling members of the handle shown disassembled but in similar positions with respect to each other when assembled.

Fig. 2 is a side elevation of a handle embodying my invention, portions being broken away to show the internal construction.

Fig. 3 is a top view of the structure shown in Fig. 2 similarly broken away.

Fig. 4 is a transverse section through a 90 handle illustrating the manner in which the leather covering is inserted into and secured to the foundation and

Fig. 5 is a transverse section of a completed handle.

As shown in the drawings, the numerals 10 indicate two similar halves of the main foundation or filling of the handle which halves are of the curved configuration common to handles of this character and which 100 may be of any suitable material, such as papier mâché, wood, fiber or the like, to which glue or cement will readily adhere, and which will enable the halves to be solidly constructed without adding undue 105 weight to the handle. I prefer to use papier mâché for constructing the foundation halves, each of which is provided with a central groove 11 adapted when the halves are brought into contacting relationship to 110

provide a pocket in which is snugly received the reinforcing metal rod 12 which is provided at its extremities with the eyes 13, adapted when the parts are assembled to align with the apertures 14 provided in the foundation halves 10.

The handle is preferably covered with a piece of leather 15, in the usual manner and is secured to the bag or other article by 10 means of metal rings 16 to the straps 17 in the usual and well known manner.

In constructing the handle the foundation halves are preferably moulded of paper pulp in a suitable mold which is provided with 15 pins to form the apertures 14 and a suitably formed rib or projection to produce the grooves 11, this operation preferably being carried out in a suitable press. After the halves have been moulded, the flat inner 20 sides are coated with glue, or cement and the halves are brought together, the metal reinforcing strip being inserted into one of the grooves.

The leather covering strip 15 is then coated 25 on its inner face with glue or cement and placed around the foundation with the overlapping ends of the strip on the upper side and with the ends arranged to overlap the upper line of juncture between the halves. 30 A flat tool having a tapered end such as indicated at 18 (Fig. 4) is then used to push the ends of the leather strip in between the foundation halves, the turned in ends being suitably coated with glue or cement, after 35 which the handle is firmly pressed together and placed aside to allow the adhesive to set, a cross section of the finished handle appearing as shown in Fig. 5. It will be understood that by coating the inner side of 40 the leather covering with adhesive not only produces a smooth finished surface but also aids to hold the entire handle together in a secure compact form.

It will be understood that although I have 45 shown and prefer to use a metal reinforcing rod in the center of the filling, that this rod may be dispensed with as the filling constructed as described is sufficiently strong to give satisfactory service without the metal 50 rod.

Having thus described my invention, what I claim as new and desire to secure by Letters Patent, is:

1. A handle of the type set forth comprising a filling consisting of a pair of similar 55 substantially solid halves constructed of fibrous material, the inner faces of said halves being provided with a groove, a metal reinforcing rod received in said groove and encased by said halves, said halves being 60 secured together by a suitable adhesive to form a compact substantially solid structure.

2. A handle of the type set forth comprising a filling consisting of a pair of similar 65 substantially solid halves constructed of fi-

brous material, the inner faces of said halves being provided with a groove, a metal reinforcing rod received in said groove and encased by said halves, said halves being secured together by a suitable adhesive to 70 form a compact substantially solid structure and a leather strip entirely covering said filling and having its overlapping ends inserted between the inner faces of said halves and retained therein by said halves when 75 said halves are secured by said adhesive.

3. A handle of the type set forth comprising a filling consisting of a pair of similar substantially solid halves constructed of fibrous material, the inner faces of said halves being provided with a groove, a metal reinforcing rod received in said groove and encased by said halves, said halves being secured together by a suitable adhesive to 80 form a compact substantially solid structure 85 a leather strip entirely covering said filling and having its overlapping ends inserted between the inner faces of said halves and retained therein by said halves when 90 said halves are secured by said adhesive, the inner side of said leather covering and its overlapping ends having a coating of adhesive thereon whereby said covering aids in securely holding the halves of the filling in a compact substantially solid structure. 95

4. A handle of the type set forth comprising a filling consisting of a pair of similar substantially solid halves, a leather strip entirely covering said filling and having its ends inserted into and secured between the inner contacting faces of said halves, and a coating of adhesive between said filling and strip whereby said strip will cause said halves of the filling to be securely held together to form a compact substantially solid structure. 100

5. A handle of the type set forth comprising a filling consisting of a pair of similar substantially solid halves having curved outer faces and substantially plane inner faces adapted to be brought into contacting engagement, and a leather strip entirely covering said filling and having its ends inserted into the secured between said plane inner faces whereby the use of projecting 110 seams or stitching is avoided, and means to securely hold said halves with said inner faces in contacting engagement whereby a compact substantially solid structure is 115 formed. 120

6. The method of making a handle of the type set forth which consists in forming a pair of similar filling or foundation halves, having curved outer faces and plane inner faces, coating the said inner faces with adhesive, placing said inner faces in juxtaposition, wrapping said halves with a leather covering, inserting the overlapping ends of said leather covering between the juxtaposed inner faces of said halves and pressing the 125 130

handle to cause the adhesive to secure said halves and covering in a compact substantially solid structure.

7. The method of making a handle of the type set forth which consists in forming a pair of similar filling or foundation halves, having curved outer faces and plane inner faces, coating the said inner faces with adhesive, inserting a metal reinforcing rod in a suitable pocket formed by said halves placing said inner faces in juxtaposition, wrapping said halves with a leather covering, inserting the overlapping ends of said leather covering between the juxtaposed inner faces of said halves and pressing the handle to cause the adhesive to secure said halves and covering in a compact substantially solid structure.

8. The method of making a handle of the type set forth which consists in forming a pair of similar filling or foundation halves, having curved outer faces and plane inner faces, coating the said inner faces with adhesive, placing said inner faces in juxtaposition, wrapping said halves with a leather covering between which and said halves a coating of adhesive is applied inserting the overlapping ends of said leather covering between the juxtaposed inner faces of said halves and pressing the handle to cause the adhesive to secure said halves and covering in a compact substantially solid structure.

Signed at New York, in the county of New York and State of New York, this 29 day of November A. D. 1922.

MORRIS JACOB GOLDMAN.
